UNITED STATES PATENT OFFICE

JOHN EARNEST JONES, OF MINNEAPOLIS, MINNESOTA

BOILER

Application filed April 16, 1928. Serial No. 270,375.

The present invention relates to a boiler construction and aims to provide a novel construction whereby the maximum degree of heat may be obtained from a given quantity of fuel.

The primary object of the invention is the provision of a novel arrangement of tubes and heating chambers to the end that the heat and other products of combustion will be caused to circulate through the tubes and heating chambers to thoroughly heat the water in the boiler, as the products of combustion pass to the chimney.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

25 Figure 1 is a longitudinal sectional view through a boiler constructed in accordance with the invention.

Figure 2 is a sectional view taken on line 2—2 of Figure 1.

30 Referring to the drawing in detail, the reference character 5 indicates the boiler casing, which has a lateral extension 6. The fire box is indicated by the reference character 7 above which is arranged a tube sheet 8 which defines a combustion chamber 9. A wall 8' extends downwardly from the tube sheet 8 and defines a water compartment 9' around the combustion chamber to heat water at this point, it being understood that the water compartment 9' is in communication with the main boiler.

40 Located at one end of the lateral extension 6, is a heating chamber 10, one wall thereof being in the form of a tube sheet 11 while the end wall thereof is curved and formed with openings defining an end tube sheet, the last mentioned tube sheet being indicated by the reference character 12.

45 The reference character 21 indicates a brick arch positioned within the heating chamber

10, the brick arch extending over the upper ends of certain tubes 16, to direct the heat laterally and partially obstruct the passage of the heat through the boiler.

50 Thus it will be obvious that due to this construction the water which surrounds the tubes of the boiler will be heated by the heat and other products of combustion through the tubes 16. The products of combustion pass from the tubes 16 into the heating chamber 10 which is surrounded by the water in the boiler whereupon the water takes up the heat at this point.

55 As the products of combustion pass through tubes 19 to the heating chamber 17, it will be seen that the water will be thoroughly heated to the end that the maximum heat may be obtained from a given quantity of fuel.

60 One end of the heating chamber 10 is closed by means of the hinged closure 13 so that the heating chamber and tubes may be readily cleaned. Draft openings 14 are provided in the closure 13, the draft openings being controlled or adjusted by means of the slide 15, so that a draft of air may be directed to the heating chambers and tubes, to aid combustion.

65 Tubes 16 have their ends disposed within the tube sheets 8 and 11 respectively, and establish communication between the combustion chamber 9 and heating chamber 10 so that heat may pass upwardly through the tubes, and into the heating chamber 10. Located at the outer end of the lateral extension 6, is a heating chamber 17, one wall of the heating chamber being formed into a tube sheet 18, the same being curved as clearly shown by Figure 1 of the drawing. Tubes 19 connect the tube sheets 12 and 18 and establish communication between the heating chambers 10 and 17.

70 As shown, the heating chamber 17 has a substantially large portion and a tapered extremity, the tapered extremity passing through the end wall of the lateral extension 6 where it provides an extension to receive one end of the chimney which is indicated at 20.

75 I claim:

80 A boiler comprising a casing having a vertical portion and a laterally extending portion at the upper end of the vertical portion

and in open communication therewith, a fire-box in the vertical portion, said fire-box having its top wall formed as a tube sheet, a combustion chamber free from water tubes, disposed within the space enclosed by the junction of said vertical and laterally extending portions and having its bottom wall formed as a tube sheet mating with the said fire-box tube sheet, vertical fire tubes connecting said tube sheets, an outwardly tapering smoke chamber disposed within the outer end of the laterally extending portion and having its inner wall formed as a tube sheet, the vertically extending inner wall of said combustion chamber being also formed as a tube sheet, horizontal fire tubes connecting said two last named tube sheets, certain of said tubes being so disposed as to direct their gases against the tapering wall of said smoke-box, a stack communicating with the outer end of said smoke-box, an inclined baffle disposed in the lower inner end of said combustion chamber and overlying the upper ends of certain of said vertical fire tubes, and a damper controlled air inlet to said combustion chamber.

In testimony that I claim the foregoing as my own, I have hereto affixed my signature.

JOHN EARNEST JONES.
